No. 817,035.

PATENTED APR. 3, 1906.

J. G. L. BORMANN,
GAS GENERATOR.
APPLICATION FILED NOV. 28, 1905.

UNITED STATES PATENT OFFICE.

JOHANN GOTTLIEB LEBERECHT BORMANN, OF CHARLOTTENBURG,
GERMANY.

GAS-GENERATOR.

No. 817,035.

Specification of Letters Patent.

Patented April 3, 1906.

Application filed November 28, 1905. Serial No. 289,522.

To all whom it may concern:

Be it known that I, JOHANN GOTTLIEB LEBERECHT BORMANN, a subject of the King of Prussia, German Emperor, residing at Charlottenburg, in the Kingdom of Prussia, German Empire, have invented new and useful Improvements in Gas-Generators, of which the following is a specification.

My invention relates to improvements in gas-generators; and it consists in the construction, combination, and arrangement of devices hereinafter described and claimed.

In the accompanying drawings, Figure 1 is a vertical sectional view of a gas-generator embodying my invention. Fig. 2 is a horizontal sectional view of the same, taken on the plane indicated by the line *a a* of Fig. 1.

In the embodiment of my invention I provide a furnace, which I will now describe. The casing 2, which is cylindrical in form, is made of metal and is provided with a metal bottom plate 3 and a metallic head 4. Within the lower portion of the casing is a lining 5, which is made of fire-clay or other refractory material. The shaft *e*, which is disposed concentrically in the furnace, is also made of fire-clay or other suitable material, and its lower portion is spaced from the lining 5, so that the reservoir *g* is formed between them. A horizontal partition 6, which is made of fire-clay or other refractory material, is supported on the lining 5 and on a shoulder formed on the outer side of the shaft *e* and separates the reservoir *g* from the intermediate portion 7 of the furnace. On the inner side of the casing 2 at a suitable distance above the horizontal partition 6 are secured brackets 8, which support the outer portion of a circular plate 9. The inner portion of said plate rests on the upper end of the shaft *e*, and it has a central opening the diameter of which corresponds with that of the upper end of said shaft and registers therewith. In the upper portion 10 of the furnace are secured supporting-brackets 11, one of which is shown in Fig. 1. The said brackets support an annulus 12, which is concentric with the shaft *e*. The upper portion 10 of the furnace is provided with a lining 13, of fire-clay or other refractory material, and the furnace-cover 14 is made of similar material, the outer portion of which rests on the lining 13. The said cover has an opening 15 above the

upper end of the shaft *e* and has a flue 16, which leads laterally therefrom. The shaft *e* 55 is provided with an upper grate *c*, which is above the annulus and rests on the plate 9, and said shaft is further provided with a lower grate *l*, which is here shown as supported on a lining 17 in the lower portion of the 60 shaft *e*. In the top of the furnace is a door *u* for use in feeding fuel to the shaft. Said door has a closure *u'* and fastening devices *u''* for detachably securing it in place. In the lower part of the shaft *e* is a fire-door *m*. A 65 door *r* serves to close the ash-pit formed in the lower portion of the shaft below the grate. A tube *q* communicates with the flue 16 and coacts therewith to permit the escape of the products of combustion when heating 70 the fuel to incandescence. Said tube is in practice connected with a suitable chimney or flue of ordinary construction, which is not here shown. Said tube has a closure *q'*, a yoke *q''*, and a screw *q'''* or other suitable securing device. 75

At the outer side of the gas-generating furnace are openings *k* for the admission of air, these openings being connected with conduits formed by pipes *i*, which are located in 80 the reservoir *g* and have their inner ends extended upwardly through the partition 6, the intermediate portion or chamber 7 of the furnace, and through the plate 8 and terminating opposite the upper grate *c* and below the 85 upper side thereof. Below the lower grate is arranged the nozzle *t'* of a serpentine pipe *t*, placed in a vaporizer *s*, and through which steam or vaporized spirit is carried under the grate *l* and discharged there. The "vaporizer" 90 *s* is so termed because the heated products of combustion therein serve to convert water or spirit in the serpentine pipe into steam or vapor, as the case may be. This vaporizer is formed in a casing *A*, which communicates 95 with the reservoir *g* through the passage *h* and is provided in its outer side with a man-hole *o*, which may be closed by means of a cover *o'* and a fastening-yoke *o''* or the like. Said man-hole permits access to the interior 100 of the vaporizer to permit the same to be cleaned. Openings *B* for the admission of air to the reservoir *k* are made in the casing 2 and the lining 5 (indicated in dotted lines in Fig. 2) and are provided with suitable covers 105 or closures *B'*, which may be removed at will.

Directly above the lower grate *l* are channels *f*, which establish communication between the shaft *e* and the reservoir *g*.

In the drawings I show a tubular boiler *T* 5 on the vaporizer *s* and also indicate a water-chamber *U* on the upper end of the boiler and a flue *b*, extending above the water-chamber. I show the latter connected with the boiler by pipes *V*, having valves *W*. I also show 10 the serpentine pipe *t* connected by a pipe *X* with the steam-space of the boiler, said pipe having a valve *Y* to regulate the passage of steam through the serpentine pipe.

The operation of my improved gas-generator 15 is as follows: The fuel placed on the lower grate *l* is ignited and burned to the point of incandescence. The products of combustion pass through the tube *q* and the chamber or flue, to which it is in practice connected. In addition to the air passing through the door *r* and grate *l* to the incandescent fuel air admitted through the openings *B* passes through the reservoir *g* and channels *f* to the fuel and facilitates the heating 20 and burning thereof to the point of incandescence. When the incandescent coke reaches the upper grate *c*, the operation of generating the combustible gas is begun. For this purpose the tube *q*, the door *r*, and 25 the apertures *B* are closed, while the holes *k* for admitting the air are left open. The air is thereby heated in the pipes *i* and enters the upper end of the shaft through the upper grate *c*. The products of distillation generated 30 during the combustion of the fuel are compelled to pass through the incandescent upper layer of coke in the shaft *e*, in which the dissociation of the heavy hydrocarbon is effected. The generated permanent gases 35 combine in the lower layer, where the mean temperature exists. The requisite high temperature to cause dissociation of the heavy hydrocarbons is reached and maintained by the means provided for insulating the shaft *e* 40 thoroughly and by effecting the combustion of the fuel at the upper layer by means of air discharged from the pipes *i*, heated to a high degree and unmixed with steam. The generated gaseous products are drawn down 45 through the lower grate *l* and carried to a suitable receiver through the flues in the boiler and water-chamber and through the flue *b* by the action of a suitable exhauster, which is not here shown. The combustion of the incandescent coke on the lower grate *l* is regulated 50 by means of the superheated steam or vaporized spirit supplied by means of the serpentine pipe *t* and nozzle *t'* through the lower

grate to the incandescent fuel. The entering steam absorbs for the purpose of its dissociation the heat which may be in the slags and coke. The oxygen of the steam thereby produced combines with the carbon to form carbon monoxide, and a complete combustion of the fuel is obtained at a moderate temperature. In building the generators the points thereof which come in direct contact with the fire are composed of highly-refractory brick. The ordinary porous red brick may, however, be used for the lower portion of the generator and for the purpose of insulation. As may be seen, any cooling of the charge may be prevented above the lower grate. The charge is permanently kept in an incandescent condition down to the lower grate and a continuous working of the generator is rendered possible.

Having thus described my invention, what I claim as new, and desire to secure by Letters Patent, is—

1. A gas-generator of the class described having a shaft with a lower grate and an upper grate, a reservoir around the shaft, channels connecting the reservoir and shaft immediately above the lower grate, and air-conduits leading from the outer air, extending into the reservoir and discharging thereinto.

2. A gas-generator of the class described, having a shaft provided with a lower grate and an upper grate, a reservoir around the shaft, channels connecting the reservoir and shaft immediately above the lower grate, air-conduits leading from the outer air, extending into the reservoir and discharging thereinto, and means to discharge steam or vapor 95 below the lower grate.

3. A gas-generator of the class described, having a shaft provided with a lower grate and an upper grate, a reservoir around the shaft, the generator connecting the reservoir and shaft immediately above the lower grate, air-conduits leading from the outer air, extending into and through the reservoir and discharging into the generator, a vaporizer, a duct extending from below the lower grate 105 through the vaporizer, and a serpentine pipe in and heated by the heated products discharged through the lower grate on their way to and through the vaporizer.

In testimony whereof I have hereunto set 110 my hand in presence of two subscribing witnesses.

JOHANN GOTTLIEB LEBERECHT BORMANN.
